(57) **CLAIM**

The ornamental design for a set of cutlery, substantially as shown and described.

DESCRIPTION

FIG. 1 is a top perspective view of a set of cutlery, showing our new design;

FIG. 2 is a top front right side perspective view thereof, shown without the fork, spoon and knife, shown in enlarged scale;

FIG. 3 is a bottom rear left side perspective view thereof, shown without the fork, spoon and knife for ease of illustration;

FIG. 4 is a front elevation view thereof, shown without the fork, spoon and knife for ease of illustration;

FIG. 5 is a rear elevation view thereof, shown without the fork, spoon and knife for ease of illustration;

FIG. 6 is a left elevation view thereof, shown without the fork, spoon and knife for ease of illustration;

FIG. 7 is a right elevation view thereof, shown without the fork, spoon and knife for ease of illustration;

FIG. 8 is a top plan view thereof, shown without the fork, spoon and knife for ease of illustration;

FIG. 9 is a bottom plan view thereof, shown without the fork, spoon and knife for ease of illustration;

FIG. 10 is a top front right side perspective view thereof, shown without the carabiner, spoon and fork for ease of illustration;

FIG. 11 is a bottom rear left side perspective view thereof, shown without the carabiner, spoon and fork for ease of illustration;

FIG. 12 is a front elevation view thereof, shown without the carabiner, spoon and fork for ease of illustration;

FIG. 13 is a rear elevation view thereof, shown without the carabiner, spoon and fork for ease of illustration;

FIG. 14 is a left elevation view thereof, shown without the carabiner, spoon and fork for ease of illustration;

FIG. 15 is a right elevation view thereof, shown without the carabiner, spoon and fork for ease of illustration;

(Continued)

FIG. 16 is a top plan view thereof, shown without the carabiner, spoon and fork for ease of illustration; FIG. 17 is a bottom plan view thereof, shown without the carabiner, spoon and fork for ease of illustration; FIG. 18 is a top front right side perspective view thereof, shown without the carabiner, spoon and knife for ease of illustration; FIG. 19 is a bottom rear left side perspective view thereof, shown without the carabiner, spoon and knife for ease of illustration; FIG. 20 is a front elevation view thereof, shown without the carabiner, spoon and knife for ease of illustration; FIG. 21 is a rear elevation view thereof, shown without the carabiner, spoon and knife for ease of illustration; FIG. 22 is a left elevation view thereof, shown without the carabiner, spoon and knife for ease of illustration; FIG. 23 is a right elevation view thereof, shown without the carabiner, spoon and knife for ease of illustration; FIG. 24 is a top plan view thereof, shown without the carabiner, spoon and knife for ease of illustration; FIG. 25 is a bottom plan view thereof, shown without the carabiner, spoon and knife for ease of illustration; FIG. 26 is a front right-side perspective view thereof, shown without the carabiner, fork and knife for ease of illustration; FIG. 27 is a bottom rear left-side perspective view thereof, shown without the carabiner, fork and knife for ease of illustration; FIG. 28 is a front elevation view thereof, shown without the carabiner, fork and knife for ease of illustration; FIG. 29 is a rear elevation view thereof, shown without the carabiner, fork and knife for ease of illustration; FIG. 30 is a left elevation view thereof, shown without the carabiner, fork and knife for ease of illustration; FIG. 31 is a right elevation view thereof, shown without the carabiner, fork and knife for ease of illustration; FIG. 32 is a top plan view thereof, shown without the carabiner, fork and knife for ease of illustration; and, FIG. 33 is a bottom plan view thereof, shown without the carabiner, fork and knife for ease of illustration.
